UNITED STATES PATENT OFFICE.

JOSEPH MARTIN SCHUTZ, OF CHICAGO, ILLINOIS, ASSIGNOR, BY MESNE ASSIGNMENTS,
TO CHARLES GILBERT HAWLEY, OF CLEVELAND, OHIO.

APPARATUS FOR SMELTING THE METALLIC DUST AND RECOVERING THE HEAT FROM BLAST-FURNACE GASES.

Application filed February 5, 1924. Serial No. 690,863.

This invention is allied to those described and claimed in my previous applications—S. N. 661,163 and S. N. 661,164, filed September 6th, 1923. To an extent it is set forth in the former; and, this application is concerned with that disclosure as applied to the burning of gases and adds steps and structures peculiar to the smelting and recovery of the metals of metallic dusts either prepared for the purpose, or contained in the gases from blast furnaces and the like, including the smelting and convenient disposal of the dusts of producer gas. As will appear my invention is adapted for the original smelting of ore that has been reduced to the form of dust with or without a pulverulent fluxing material; but its more immediate use is in the reduction and recovery of the metallic dust contained in blast furnace gases and in the conservation of the heat of such gases.

The principal objects and effects of my invention will appear hereinafter.

My invention will be readily understood on reference to the accompanying drawings, in which

Fig. 1 is a vertical longitudinal section of apparatus suitable to, and embodying my invention, as associated with steam boiler furnaces for the use of the heat of the gases;

Fig. 2 is the front elevation thereof, one-half in section on the line 2—2 of Fig. 1;

Fig. 3 is a horizontal section on the line 3—3 of Fig. 1; and,

Fig. 4 is a vertical cross section of a heating furnace, illustrating a modified form of my invention and smelting burner in which supplementary or gas enriching fuel is employed.

According to my invention the smelting apparatus or burner proper is arranged within a refractory walled fire chamber, 2, in which the heat of the burning gases is utilized; as by a steam boiler 3. The part marked 4, is a duct or pipe through which combustion supporting air under pressure is supplied to the smelting burner. The part marked 5, is a like duct or pipe; through which the combustible gas, also under pressure, is supplied to the burner. In practice these ducts, 4 and 5, may be of the same capacity, for in most cases equal volumes of air and combustible gas are required to maintain combustion in the burner. How-

ever, in the air damper or valve, 6, and the familiar gas-pressure operated device, 7, connected with the gas duct by the pipe 8, I have provided means for either equalizing or regulating the proportions of air and gas; as may be required by the varying richness of the gas supplied to duct 5. Further, this device, (6, 7, 8) is particularly desirable in the case of smelting burners which because of the combustible leanness of the gas employ a coincident stream of gas enriching fuel, either coal or oil. Such a use is provided for in the fuel tuyère, 9, of Fig. 4.

With this introduction I shall first describe the construction and operation of the burner proper and follow that with a description of the dust smelting operation.

The ducts 4 and 5, preferably positioned one above the other, communicate with respective chambers 4' and 5', preferably having the form of volutes or scrolls, as well shown in Fig. 3. These are co-axial, and one above the other. Their outer walls are composed of refractory brick, 10. Their inner walls may comprise metal scrolls, 10' and groutings, 10" of a material such as sand, filling the spaces between the metal scrolls and the conveniently cylindrical brick wall 10. The separating floor, 11, between the scrolls, may be made of suitably molded or shaped segmental fire brick; with a floor covering 11', closing any cracks therein. The part, 12, is a relatively shallow circular bowl, positioned below the floor, 5" of the gas chamber or scroll, 5', and preferably composed of suitably moulded or shaped refractory brick. At the center, the bowl has a discharge hole, 12'. Below that is a bucket tunnel, 13, the use of which will be explained. The top of the scroll 4' is formed by the cover ring, 14, preferably composed of segmental brick, resting on an easily removable sectional metallic cover, 14'; which normally the brick protects from the intense heat in the chamber 2. Coaxially with the bowl 12 and the scrolls 4' and 5' I provide two multiple tuyère rings; 15 and 16, one for each scroll. These rings may be identical. Each is composed of a large number of overlapping staves or blades, 17, separated by narrow tuyère openings or spaces, 18. The staves are much longer than they are wide and are closely spaced; and therefore the tuyère openings are no more than vertically elongated tangential slits or

cracks. But being many, the aggregate areas of the vertically elongated tuyère openings substantially equal, and may somewhat exceed, the cross sectional area of respective 5 air and gas ducts. The blades, 17, are made of metal, preferably cast iron, and are suitably secured together to make up the complete tuyère ring, in each case. Surprisingly, the tuyère rings may be made of metal 10 notwithstanding the intense heat generated within the tuyère rings as about to be explained; for the relatively cool air and gas passing through the narrow tangential tuyères absorbs the heat from the metal 15 blades and in each case adequately protects them from burning. The tuyère rings are of the same diameter as the top of the bowl 12, on the top or rim of which the tuyère ring, 16, rests. The top of the ring, 16, meets 20 and supports the inner margin of the separating floor, 11, which contains a large central opening 11" of like size. The floor 11, in turn supports the co-axial tuyère ring 15, and that in turn supports the inner margin 25 of the brick cover ring, 14. The central opening 14" in the latter, is somewhat smaller than the interior of the tuyère rings, and therefore the inner margin of the cover ring forms or presents an annular overhanging abutment portion, 19, at the top of 30 the tuyère ring 15. This portion 19 when next referred to will be called an annular abutment, a term which explains its important function in the best performance of the 35 invention.

The whole structure of the burner rests on the floor of the fire chamber 2, or if desired may constitute that floor.

In practice I first heat the burner internally by making a light fire in the bowl 12, and turning on a blast of pressure air through the trunk 4; scroll 4' and tuyère ring 15. Entering through the many tangential tuyères, 18, the pressure air is instantly organized 40 into a thin walled hollow column of a thickness little exceeding the width of the slit-like tuyères. Of necessity the air moves in the direction instituted by the tangential tuyères, that is, it must needs move forward 45 about and upon the inner periphery of the tuyère ring. Because of the centrifugal thrust developed by this enforcement of rotary travel within the tuyère ring, the incoming air is forcibly banked against the 50 ring 15, and but slowly if at all expands toward the central axis of the ring. A dense whirling column of air is thus organized and maintained upon the inner periphery of the tuyère ring. The presence 55 of the annular abutment 19, at the top of the ring, prevents the expansion or movement of the banked air in that direction and therefore the rapidly rotating column of air 60 constantly augmented by the entrance of fresh air through the tangential tuyères,

moves downward and in rapidly whirling condition enters the top of the bowl 12. There it acts with blow pipe effect upon the initial fire in the bowl and thus combustion in the bowl is hastened, high temperatures 70 are attained from the light initial fire, and the internal brick work of the burner is quickly brought to a temperature that will best admit of the institution of the real processes of combustion and smelting. 75

Such process of combustion begins with the admission of combustible gas before the initial fire is exhausted, so that the mixture of air and gas may be ignited therefrom. The combustible gas at a pressure corresponding to that of the pressure air, is admitted through the trunk 5, scroll 5', and tangential tuyère ring 16. The action of the gas within the ring is identical with the described action of the air admitted through the ring 15, save that the upward or direct outward loss or expansion of gas need not be interfered with by a substantial annular abutment, but instead, is prevented by abutment with the downwardly moving whirling column of air from the upper tuyère ring. Thus the whirling column of gas is also forced downwards. Obviously the two columns of air and gas organized by the use of the slit-like tangential tuyère rings, move 95 downward towards the bottom or bowl 12, and in so moving the air and combustible gases are forcibly and intimately mixed. Being ignited as explained, the forcibly-made mixture of air and gas burns in a 100 whirling condition and meeting and re-acting against the bottom bowl, the burning, whirling column finds escape upward along the axis of the burner and out through the opening within the annular abutment portion 19, in the top or cover 14. Meanwhile the central or outgoing burning column radiates heat to the freshly forming columns of air and gas within the tuyère rings and thus hastens combustion, insures perfectness of 105 combustion and makes it possible to steadily maintain combustion within the burner at 110 all rates of air and gas supply. 115

Although the entering air and gas highly expand under the almost instantaneous heating to which they are subjected by the outgoing whirling column of flame, the centrifugal vigor of the tangentially organized air and gas columns is always sufficient to insure their complete admixture. After such heating and admixture the further element of time required for the completion of combustion becomes of little importance, because an adequately high temperature is certain to be always maintained within the burner, and the actual final combustion of the gaseous products may be conducted and prolonged to the desired degree in any suitable fire chamber (such as 2) external to the burner proper. As here shown the heat of 125 130

the combustion is utilized in the steam boiler 3.

So much of my invention being understood it should now be obvious that any 5 particle of fusible matter which may enter the burner either with the air or with the gas will be fused almost instantly by the intense heat in the burner and will be whirled or thrown against the inner walls 10 thereof. This being understood the remainder of the process and its several uses concerning the clarification of the gas flames and smelting of metals may now be described.

15 Receiving, for example, blast furnace gas with its burden of metallic dust and the burner being hot, I direct the gas into the burner through the duct 5; meantime maintaining a proportioned flow of pressure air 20 through the duct 4. The air and gas being brought into intimate admixture as before described, combustion proceeds within the burner at such temperatures as to melt or fuse the particles of dust. The relatively 25 minute peripheral subdivision of the gas by means of the multiple tuyère ring, first has the effect of distributing and positioning all dust particles quite uniformly upon the exterior of the whirling column of gas with- 30 in the tuyère ring; that is, the dust particles are initially and quite uniformly distributed upon or against the inner surfaces of the tuyère ring. Centrifugal force tends to maintain this initial distribution of the dust 35 particles so filtered or strained from the body of gas and deposited on the inner surface of the tuyère ring. The force of gravity and the downward thrust of the whirling columns of air and gas cause the particles 40 to move spirally downward in the presence of the outgoing central column of flame, from which much heat is received. The relatively cool incoming gas doubtless serves to withhold the particles from complete 45 fusion until they reach the bottom bowl. There, the heat is so intense that the gathered and constantly gathering particles 50 are quickly fused or melted. A film-like mass of molten metal with a superimposed 55 film of dross or slag is thus formed on the bottom of bowl, providing a new surface for it, against which the burning gases whirl and react into the described central outgoing column of flame. Clearly, the refrac- 60 tory bottom is always kept hot. The accumulation of molten metal and slag proceeds rapidly and is discharged in a continuous stream through the hole 12' in the bottom of the bowl.

65 As before stated, I prefer that the hole 12' shall be central; this to the end that the molten material shall have uniform opportunity of discharge from all parts of the bowl, 12; and for the further reason that 65 at times it may be necessary to introduce

pulverized coal, or oil, (as through tuyère 9) to enrich a lean gas, in which case the periphery of the bowl should be imperforate, lest the added fuel be permitted to escape from the bowl before it is consumed.

70 As contrasted with those systems in which the gas is cooled by a washing process that removes the dust, my invention takes the gas at whatever temperature it comes from the blast furnace or other source; and thus 75 the contained or initial heat of the crude gas is saved, and obviously the combustion in the burner is advantageously hastened.

80 The valuable metal contained in blast furnace dust is of such quantity and quality as to be well worth saving; indeed the saving herein prescribed offsets a considerable part of the cost of blast furnace operation.

85 Ordinarily the walls and contents of the fire chambers, ovens or stoves in which the gas is burned, receives much fused and sintered dust; and after relatively short runs are so befouled as to require shutdowns, expensive cleanings and frequent reconstructions. A distinct advantage of my 90 invention, one of quite as much importance as the saving of metal, resides in the above described clarification of the gases prior to their release into the fire chamber. The dust having been fused and removed in the 95 described burner, it is obvious that the burning gases leave the burner in a clean, clear condition and that the operation of the fire chamber, oven, stove, or boiler may be continued indefinitely, without regard to the 100 befouled condition of the gases furnished to the burner or burners.

105 Save that the described clarification of the gas sequentially follows the smelting of the dust, such clarification very properly might be set forth as the chief object of my invention; such is the industrial importance of the gas clarifying operation.

110 Whenever the dust burdened gas is too poor or lean in combustibles to maintain the proper combustion, I introduce enriching fuel through one or more fuel feeding tuyères, 115 such as the tuyère 9 shown in Fig. 4. In some cases the bowl 12' may be somewhat deepened; to slightly increase the period or time of the exposure of the incoming fuel on the walls of the burner bowl. The added fuel merely augments the combustibility of the mixture of air and gas. The fuel is held at the periphery of the bowl by the 120 whirling motion of the gaseous mixtures and escapes only as it is decomposed and combusted. Any ash in the fuel is quickly fused and directly added to the molten mass or slag from the metallic dust. In other respects the process is the same as before described.

125 By adding another kind or kinds of pulv- verulent ore, or metal, to the stream of dust laden gas flowing through the duct 5, I 130

- easily convert the smelted dust into any desired alloy. As the mixing of the gas and different kinds of metallic dust is easy of mechanical accomplishment and is the only 5 step required for the production of alloys, for example, manganese products and the like, I have thought it unnecessary to illustrate the obvious mixing device that feeds the added dust to the gas duct 5.
10. Where a clean gas is available, I employ the same in the above described manner, but for the original smelting of pulverized metallic ores. The use or non-use of pulverulent fluxing material is determined by the 15 character of the metallic dust to be smelted. Obviously the process remains the same, however the dust is admixed with the stream of combustible gas, whether natural or artificial.
20. Similarly, when equipped with a pulverized coal or oil burning furnace of the kind illustrated in my application S. N. 661,164, the same may be employed for the original smelting of ores by feeding the pulverized 25 ore directly into that furnace, preferably through the agency of the air blast and the multiple tangential tuyère ring. When coal is the fuel employed the quantity of molten slag is obviously increased; otherwise the 30 smelting process, the combustion process and the utilization of the heat of the combustion are as above described.

By preference a mold 20 is placed beneath the discharge hole 12' of the burner to receive the molten metal and slag therefrom. A very good gravity separation of molten 35 metal and slag takes place in the mold and by changing the molds as rapidly as they are filled the material may be very conveniently 40 "pigged" or cast into blocks. When cooled the slag easily separates or breaks off from the underlying metal, leaving a pig of metal that may be utilized as would any other mass of the same metal or alloy. For convenience 45 the "pigging" molds 20 are metal buckets or

"chills" arranged in the form of a traveling belt that slowly conveys the "pigs" from the tunnel 13, to the point of their discharge. Obviously any suitable device, mold, progressive furnace, or metallurgical hearth 50 may receive the molten metal directly from the described smelting burner.

It should be explained that the annular abutment 19 of the burner may be done away with without materially interfering 55 with the herein described smelting operation; but in such case much of the pressure air will escape into the fire chamber direct from the top of the burner and nicety of combustion and ease of control will be lost. Hence it seems best always to employ the abutment 60 19 or at least some operating equivalent that will compel the described downward travel of both the air and gases before they can escape from the burner.

Further, my invention may be modified and used in other ways by those who are skilled in the art; and, all without departing from the spirit or scope of the invention as herein described and claimed.

Having thus described my invention, I claim as new and desire to secure by Letters Patent:—

1. The herein described gas burning furnace comprising a bottom bowl, in combination with superposed multiple-tuyère rings and an overhanging annular abutment, and means for supplying pressure air and gas through respective tuyère rings.

2. The herein described gas burning and dust smelting furnace comprising a refractory bottom bowl containing a central metal-discharge hole, in combination with superposed multiple-tuyère rings and an overhanging annular abutment, and means for feeding air and gas to respective rings.

In testimony whereof I have hereunto set my hand this 31st day of January, A. D., 1924.

JOSEPH MARTIN SCHUTZ.
